(No Model.)

J. W. COOPER.

PHOTOGRAPHER'S CHAIR.

No. 360,855.

Patented Apr. 12, 1887.

UNITED STATES PATENT OFFICE.

JOHN W. COOPER, OF ATLANTA, GEORGIA, ASSIGNOR TO COLUMBUS W. MOTES, OF SAME PLACE.

PHOTOGRAPHER'S CHAIR.

SPECIFICATION forming part of Letters Patent No. 360,855, dated April 12, 1887.

Application filed October 13, 1886. Serial No. 216,121. (No model.)

To all whom it may concern:

Be it known that I, JOHN W. COOPER, a citizen of the United States, residing at Atlanta, in the county of Fulton and State of Georgia, have invented certain new and useful Improvements in Photographer's Chairs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to an improved chair designed for the use of photographers, whereby they can adjust the subject to any desired posture without any discomfort on the part of said subject.

20 The object is the construction of a chair which is adjusted in all its parts so it can be accommodated to different-sized persons and to any required pose.

The improvements consist in the novel features of construction, hereinafter more fully set forth, claimed, and shown in the annexed drawings, in which—

Figure 1 is a perspective view of a chair of my construction embodying my improvements. Fig. 2 is a side elevation of the same, parts broken away, showing the internal construction. Fig. 3 is a sectional view on the line $\alpha - \alpha$ of Fig. 1. Fig. 4 is a perspective view of the end of the back-supporting bar and the means for connecting it with the back. Fig. 5 is a detail perspective view of the end of the seat-bar and the seat-casting, and Figs. 6 and 7 are detail perspective views of the devices for attaching the arms to the back. Fig. 40 8 is a detail view of the foot-rest.

The chair comprises the base A, having legs A², of usual construction, and the reach A', the back B, and the seat C. The seat-support C' has its upper end reduced and fitted 45 in a casting, c, secured to the under side of the seat, and is provided with a series of teeth, c', at the base of the reduced end, which engage with corresponding teeth in the lower end of the casting c and hold the seat in an 50 adjusted position against any accidental dis-

placement. When it is desired to adjust the seat about its support as an axis, it (the seat) is lifted so as to disengage the teeth of the casting c from the teeth on the support, and the desired adjustment having been made, the seat 55 is lowered and will be held in such position by the re-engagement of the teeth.

The seat-support has a series of teeth formed longitudinally on one side, and is mounted in a vertical opening in the base A. The gear-wheel d, mounted upon a shaft D, journaled in the base to one side of the seat-support, meshes with the latter and serves to raise and lower it, as occasion may require. A second shaft, E, journaled in the base at a distance 60 from the shaft D, is provided with a crank, E', on its outer end, by which it is rotated, and has a gear-wheel, e, secured thereon, which meshes with the gear-wheel d, and imparts motion thereto when moving the seat- 70 support in either direction.

The pawl f, engaging with the ratchet-wheel f', keyed upon the shaft D, prevents retrograde movement thereof and holds the seat-support in an adjusted position. It is 75 keyed to a shaft, F, which projects through a side of the base, and has a handle, f², secured to its outer end, to be grasped by the hand to disengage the pawl of said ratchet-wheel when it is desired to lower the seat-support. 80

The ratchet-segment G projects forward from the base, and may be an integral part thereof, or separate and secured thereto, as desired. The foot-rest support G' is bifurcated at its upper end and embraces the ratchet-segment, to which it is pivotally secured and held in an adjusted position by the pawl g, pivoted in said bifurcated end, engaging with one of the teeth in the segment. The foot-rest G' is pivoted to the lower outer end of its support 85 G', and is adjustably connected therewith by the set-screw g', passing through its rear portion and bearing upon the lower rear end of said support G', as shown. By this means the foot-rest has a twofold adjustment, one about 90 its pivotal connection with the support and the other with the support.

The reach A' has its upper end vertically apertured to receive the back-rod support H, which is adjustably held therein. The shaft 100

a, journaled in the upper end of the reach to one side of the vertical aperture, has one end extended and provided with a crank, *a'*, and has a gear-wheel, *a''*, mounted thereon, which meshes with the teeth *h*, formed in one side of the back-rod support for adjusting the latter vertically, when required. Said back-rod support is held in an adjusted position by the pawl *a'*, engaging with the ratchet-wheel *a''*, keyed to said shaft *a*. The rear end of said pawl is extended and projects beyond the reach, so it can be readily pressed upon and be disengaged from said ratchet when it is desired to lower the back-rod support.

15 The head *I*, secured to the upper end of the back rod-support, is transversely apertured to receive the back-rod *J*, which is provided with teeth on one side engaged or meshing with the gear-wheel *j*, secured upon the shaft *j'*, journaled in the head to one side of the transverse aperture, and having one end extended beyond the side of the head and provided with a crank, *j''*, by which said shaft is turned and an adjustment of the back-rod effected. The set-screw *j'*, passing through a side of the head, is adapted to engage with said back-rod and hold it in an adjusted position. The outer end of the back-rod is bifurcated, and fits between lugs *k*, extending from a casting, *K*, secured to the rear of the back. A space is left between one side of said bifurcated end and a side of one of the lugs, in which is fitted the cam-head *l* of the lever *L*, which is mounted upon a bolt passing through the lugs of said casting *K* and between the bifurcated end of said back-rod. By this means, when the lever is turned into a horizontal position, the back can be adjusted to any position desired. When the desired adjustment of the back is effected, 40 the lever is again turned into an approximately-vertical position and causes a binding between the bifurcated end of the back-bar and the lugs of the castings, which will hold said back in its adjusted position.

45 The sides of the back are provided with castings *M*, which have openings *m* formed therein and designed to receive the projection *n* of a corresponding casting, *N*, secured to the arms, by which the latter are secured to the back in 50 such manner that they can be readily removed when it is desired to use the chair without arms. The opening *m* is elongated, preferably, in the direction of length of the casting, and the projection *n* has a corresponding elongated head, forming a neck between it and the casting *N* equal to the width of said open end. To secure the arm in place, the head of the 55 projection *n* is passed through the opening *m* till the neck portion corresponds with the plane

of said casting *M*, when the arm is partially 60 turned, bringing the head of the projection crosswise of the opening in the casing *M*.

Having thus fully described my invention, what I claim, and desire to secure by Letters Patent, is—

65 1. The combination, with the foot-rest support and the foot-rest pivotally connected with its lower end, of the set-screw interposed between said support and rest, substantially as and for the purpose set forth.

70 2. The combination, with the base having a ratchet-segment and the foot-rest support having its upper end bifurcated, embracing the ratchet-segment and pivotally connected therewith, of a pawl pivoted within the bifurcated end and engaging the segment to hold the foot-rest support at an adjusted position, the foot-rest pivotally connected with the lower end of its support, and the set-screw interposed between it and said support, substantially as and for the purpose described.

75 3. The combination, with the base having a reach vertically apertured at its upper end, the back-bar support having teeth longitudinally thereof mounted in said opening and provided with a transversely-apertured head, the ratchet-wheel supported in the outer end of the reach for raising and lowering said back-bar support, the pawl for holding the wheel at an adjusted position, the back-bar having teeth mounted in the opening of said head, the pinion for adjusting said bar, and the back carried on the outer end of the back-bar, substantially as described.

80 4. The combination of the base having a reach through the upper end of which a vertical aperture is formed, the back-bar support adjustably held in said opening and having a transversely-apertured head, the back-bar adjustably held in the opening of said head, and the back secured to the end of the back-bar and adjustable relative thereto, substantially as and for the purpose set forth.

85 5. The combination of the back-bar having a bifurcated end, the casting secured to the seat-back and having lugs extending therefrom embracing the bifurcated end of the back-bar and transversely apertured, and the cam-lever pivotally supported between the lugs of the casting and interposed between them and a side of the bifurcated end of the bar, substantially as and for the purpose described.

90 In testimony whereof I affix my signature in presence of two witnesses.

JOHN W. COOPER.
